[57] CLAIM

The ornamental design for a combination cigarette and
lighter case, substantially as shown and described.

DESCRIPTION

FIG. 1 is a perspective view of a combination cigarette
and lighter case, showing my new design;
FIG. 2 is a left side elevational view thereof;
FIG. 3 is a front elevational view thereof;
FIG. 4 is a right side elevational view thereof;
FIG. 5 is a rear elevational view thereof;
FIG. 6 is a top plan view thereof;
FIG. 7 is a bottom plan view thereof;
FIG. 8 is a left side elevational view with a portion
shown broken away to clearly disclose the interior.
The broken line disclosure of a cigarette package and
lighter shown in FIG. 1 is for illustrative purposes only
and forms no part of the claimed design.
